UNITED STATES PATENT OFFICE.

CHARLES O. BOWEN, OF DORA, ALABAMA, ASSIGNEE TO WALTER B. MILLER,
TRUSTEE, OF WALLINS CREEK, KENTUCKY.

ELECTRIC LOCOMOTIVE.

Application filed May 22, 1926. Serial No. 111,060.

This invention relates particularly to electric locomotives used for hauling mine cars and for similarly industrial work, the locomotive receiving power from an overhead 5 trolley wire through a trolley pole mounted on the locomotive.

The object of the invention is to provide mechanism whereby the trolley pole may be conveniently controlled by the motorman.

10 This mechanism is especially adapted to so controlling the locomotive as to avoid accidents to the equipment and to workers.

In the accompanying drawings,

15 Fig. 1 is a side elevation showing the forward part of a mine locomotive to which my improved trolley pole control mechanism is applied;

20 Fig. 2 is a plan of the structure shown in Fig. 1;

25 Fig. 3 is an upright transverse section on the line, 3—3, of Figs. 1 and 2, looking toward the right;

30 Fig. 4 is an upright section on the line, 4—4, of Fig. 3, looking toward the right;

35 Fig. 5 is a horizontal section on the line, 5—5, of Fig. 4;

40 Fig. 6 is a horizontal section on the line, 6—6, of Fig. 4.

Referring to said drawings, A is the body 45 of the locomotive. A¹ is the front platform. A² is the front buffer. A³ is a part of one of the front wheels.

B is the trolley pole. C is a bracket having 50 an upright flat body and an upper horizontal flange, C¹, and a lower horizontal flange, C². Said bracket is secured to the front upright face, A⁴, of the locomotive body, A, by means of cap screws, C³.

A cylindrical barrel is composed of an upper section, D, and a lower section, D¹. The meeting ends of these sections overlap and are screw-threaded to join them rigidly upon 55 each other. The upper section, D, extends through the upper flange, C¹, in manner to permit rotation of said section in said flange.

Above said flange, a hand wheel, W, has a hub, D², surrounding the section, D. Said hub is adjustably secured to said section by means of a set-screw, D³. The lower section, 60 D¹, extends through the lower flange, C², in manner permitting rotation in said flange. A cap, D⁴, is screw threaded around the lower end of the section, D¹. The hub, D², and

the cap, D⁴, are separated from each other far enough to allow some endwise movement 55 of the barrel.

A ring, D⁶, is threaded around the lower end of the barrel section, D, and forms the upper half of a ball bearing. A ring or collar, D⁷, loosely surrounds the section, D¹, 60 and forms the lower half of said bearing. Balls, D⁸, are confined in annular grooves or race-ways formed in the opposing faces of said rings. An expanding coiled spring, D⁹, loosely surrounds the barrel section, D¹, 65 and bears against the upper face of the lower flange, C², and against the lower face of the bearing collar, D⁷. The upward pressure of the spring, D⁹, is to be sufficient to largely or substantially support the barrel whereby 70 frictional contact between the hub, D², and the upper face of the flange, C¹, is reduced or avoided, and rotation of the barrel is resisted only by the small frictional resistance exerted by the roller bearing. The upward 75 pressure of this spring, D⁹, may be varied by turning the threaded upper ring, D⁶, on the barrel section, D, for moving said ring upward or downward, according to whether the spring pressure is to be increased or diminished. It is intended that the spring, D⁹, and the lower ring, D⁷, will not rotate. Thus 80 the barrel and the parts seated thereon are supported on a yielding or cushioned bearing. 85

The upper end of the section, D, has a horizontal head or cross wall, D⁵, which is centrally apertured to form a bearing for an upright slidable rod, E. The cap, D⁴, is centrally apertured to make a bearing for the 90 lower part of said rod, E. Immediately above the bottom of the cap D⁴, said rod has an annular shoulder, E¹, which is adapted to rest on said bottom and thereby limit downward movement of said rod. 95

A channel form chair, F, has its bottom web secured immovably on the upper end of the barrel section, D. Said chair has two upright parallel flanges. An expanding coiled spring, E², surrounds the rod, E, within the 100 barrel and has its lower end resting on the annular shoulder, E¹, while its upper end bears against the cross wall, D⁵, of the upper barrel section, D. Said spring tends to constantly press the rod, E, downward as 105 far as permitted by the annular shoulder, E¹.

But said spring is adapted to yield to permit upward movement of the rod, E, when lifting force is applied to the lower end of said rod, as will be described further on.

5 The lower end of the trolley pole, B, extends between the flanges of the chair, F, and is pivoted to said flanges by a pintle, B¹, extending horizontally through said flanges and said pole. The pole extends into the 10 space between the flanges of the chair and said extended portion is bifurcated, the rod, E, being between the arms thus formed. A nut, E³, is threaded around the rod, E, below this part of the pole, and a nut, E⁴, is threaded around said rod above this part of the 15 pole. These nuts are spaced from each other a suitable distance to so engage the pole as to permit the pole to tilt when the rod, E, is moved endwise. As above indicated, the 20 spring, E², normally holds the rod, E, in its lower position whereby the lower end of the trolley pole is held down and the upper or long end of the pole is held in the elevated position. It will now also be seen that while 25 the locomotive is in motion on the track, depressions and elevations in the trolley wire will cause downward and upward movement of the upper end or long arm of the trolley pole, such movement of the trolley pole being 30 permitted by the yielding of the spring, E, for endwise movement of the rod, E. Such yielding movement of the trolley pole is also needed when the locomotive passes over irregularities in the track.

35 It will now be seen that there are two elements which tend to support the trolley pole in contact with the trolley wire and both of which elements may yield to allow downward movement of the trolley pole during the travel of the locomotive, these two 40 elements being the spring, D⁹, and the spring, E².

For lowering the upper or free end of the trolley pole, B, away from the trolley wire 45 or similar electricity conductor, the rod, E, is to be pushed upward, whereby the nut, E³, is made to push the fork of the trolley pole upward, whereby the trolley pole is made to tilt on the pintle, B¹.

50 The horizontal bar, G, is used to lift the rod, E. On one end of said bar is a socket, G¹, in which rests the lower end of said rod. The other end of said bar is pivoted at G² to the 55 upper end of a link, G³, the lower end of which is pivoted at G⁴ to a horizontal base bar, G⁵, which is secured to the face, A⁴, of the locomotive body by means of cap-screws, G⁶. Near the end of the bar, G, which bears the socket, G¹, the upper end of a toggle 60 link, G⁷, is coupled to said bar. The lower end of said link is coupled to the upper end of the companion toggle link, G⁸, the lower end of which is coupled to the base bar, G⁵. The toggle links are inclined away from the 65 upright link, G³. To effect upward movement

of the adjacent end of the horizontal bar, G, the meeting ends of the toggle links are to be moved toward the link, G³. This is accomplished by means of a horizontal rod, H, having one end coupled to the toggle at the 70 meeting ends of the links and having its other end coupled to the short arm, H⁴, of a horizontal, angle lever, H³, the arm, H⁴, being horizontal and at an angle to the body of said lever whereby a bell crank is formed. At said angle said lever is pivoted to the horizontal arm of a bracket, H², which is fixed on the base bar, G⁵. The long arm of the lever, H³, is supported by a horizontal rack comprising a lower member, H⁵, and an upper member, H⁶. The lower member is of inverted U-form and has one arm secured to the base bar, G⁵, by means of a bolt or rivet, H⁷, and has its other arm secured to the locomotive body platform, A¹, by means of a cap screw, H⁸. The upper member, H⁶, is also of inverted U-form and is placed upon the lower member, H⁵, the arms of the upper member overlapping the arms of the lower member and being suitably secured to said 80 arms.

The angle lever, H³, rests between the rack member, H⁵, and the rack member, H⁶, and is allowed sidewise movement between said members. Moving the free end of the lever, H³, forward will cause movement of the link or rod, H, in the direction for folding the toggle and removing lifting pressure from the rod, E. Moving the free end of said lever rearward will cause the straightening of the toggle and the lifting of the adjacent end of the bar, G, whereby the rod, E, is lifted and the trolley pole is tilted for lowering the outer end of the pole. The rack, H⁵, H⁶, has upright apertures, H⁹, which are adapted to receive pins, H¹⁰, adapted to serve as stops for limiting the movement of the lever, H³. On the link, H, is a turnbuckle, H¹, by means of which the length of said link may be varied to adjust this lifting mechanism relative to the rod, E.

The lever, H³, is so located as to allow it to be shifted promptly by the foot of the motorman for prompt releasing of the trolley pole from the trolley wire, if this becomes desirable while the locomotive is running. This lever, H³, may also be promptly used in this way when the trolley pole becomes accidentally disengaged from the trolley wire. In that case it is desirable to promptly lower the trolley pole to avoid damage to the pole and to any structure at the mine ceiling. When the trolley pole has thus been accidentally disengaged from the trolley wire, the motorman first effects the lowering of the trolley pole and then, by turning the hand wheel, W, swinging the pole laterally until it is in position to be allowed to rise to engage the trolley wire.

Whenever the trolley pole is to be changed

from one trolley wire to another, the motor-man may, without changing his position, first lower the trolley pole by moving the lever, H^3 , and then swinging the trolley pole side-
5 wise by engaging the hand wheel, W . Whenever it is desired to keep the trolley pole in the lowered position, it is brought into that position by moving the lever, H^3 , in the appropriate direction and then secured in that
10 position by means of a stop pin, H^{10} , inserted in one of the apertures, H^9 .

I claim as my invention:

1. In an electric locomotive, the combination of a pivoted trolley pole, downward-
15 acting elastic means constantly tending to tilt the pole to lift its free end, and operator-actuated means adapted to act upward in opposition to said elastic means to cause the tilting of said pole to lower its free end, sub-
20 stantially as described.

2. In an electric locomotive, the combination of a pivoted trolley pole, elastic means constantly tending to tilt the pole to lift its free end, and operator-controlled means in-
25 cluding a toggle adapted to act in opposition to said elastic means to cause the tilting of said pole to lower its free end, substantially as described.

3. In an electric locomotive, the combination of a pivoted trolley pole, downward-acting elastic means constantly tending to tilt the pole to lift its free end, and means including an operator-actuated lever adapted to act upward in opposition to said elastic
30 means to cause the tilting of said pole to lower its free end, substantially as described.

4. In an electric locomotive, the combination of a pivoted trolley pole, downward-acting elastic means constantly tending to tilt the pole to lift its free end, means including an operator-actuated lever adapted to act upward in opposition to said elastic means to cause the tilting of said pole to lower its free end, and means for securing said lever, sub-
40 stantially as described.

5. In an electric locomotive, the combination of a trolley pole pivoted between its ends, a reciprocable rod having one end in engagement with the short arm of the pole, a spring constantly tending to press said rod away from the pole, and operator-actuated means engaging said rod for pressing said rod upward in opposition to said spring, sub-
50 stantially as described.

55 6. In an electric locomotive, the combination of a trolley pole pivoted between its ends, a reciprocable rod having one end in engagement with the short arm of the pole, a spring constantly tending to press said rod away from the pole, a bar hinged at one end and having its other end in engagement with the free end of said rod, and operator-
60 controlled means for moving the free end of said bar, substantially as described.

65 7. In an electric locomotive, the combina-

tion of a trolley pole pivoted between its ends, a reciprocable rod having one end in engagement with the short arm of the pole, a spring constantly tending to press said rod away from the pole, a bar hinged at one end and having its other end in engagement with said rod, and operator-controlled means including a toggle for moving the free end of said bar, substantially as described.

8. In an electric locomotive, the combination of a trolley pole pivoted between its ends, a reciprocable rod having one end in engagement with the short arm of the pole, a spring constantly tending to press said rod away from the pole, a bar hinged at one end and having its other end in engagement with said rod, means including a toggle for moving the free end of said bar, and an operator-controlled lever in operative relation with said toggle mechanism, substantially as described.

9. In an electric locomotive, the combination of an upright rotatable support, a trolley pole pivoted on said support, downward-acting elastic means constantly tending to tilt the pole to lift its free end, and operator-actuated means adapted to act upward in opposition to said elastic means to cause the tilting of said pole to lower its free end, substantially as described.

10. In an electric locomotive, the combination of a stationary bracket, a trolley pole pivoted on said bracket, downward-acting elastic means constantly tending to tilt the pole to lift its free end, and operator-actuated means adapted to act upward in opposition to said elastic means to cause the tilting of said pole to lower its free end, substantially as de-
95 scribed.

11. In an electric locomotive, the combination of a bracket, an upright rotatable support on said bracket, a trolley pole pivoted on said support, downward-acting elastic means constantly tending to tilt the pole to lift its free end, and operator-actuated means adapted to act upward in opposition to said elastic means to cause the tilting of the pole to lower its free end, substantially as described.

12. In an electric locomotive, the combination of a bracket, an upright rotatable support on said bracket, a spring supporting said support, a trolley pole pivoted on said support, downward-acting elastic means constantly tending to tilt the pole to lift its free end, and operator-actuated means adapted to act upward in opposition to said elastic means to cause the tilting of the pole to lower its free end, substantially as described.

13. In an electric locomotive, the combination of a bracket having two apertured flanges, a barrel extending through the apertures of said flanges and rotatable therein, means limiting upright movement of the barrel, a rod extending through said barrel and making engagement with the pole, a spring in engagement with said rod to tend

to press the rod downward, and operator-controlled means for pressing said rod upward, substantially as described.

14. In an electric locomotive, the combination of a bracket having two apertured flanges, a barrel extending through the apertures of said flanges and rotatable therein, a spring supporting said barrel, means limiting upright movement of the barrel, a rod extending through said barrel and making engagement with the pole, a spring in engagement with said rod to tend to press the rod downward, and operator-controlled means for pressing said rod upward, substantially as described.

15. In an electric locomotive, the combination of a bracket having two apertured flanges, a barrel extending through the apertures of said flanges and rotatable therein, means limiting upright movement of the barrel, a chair seated on said barrel, a trolley pole pivoted on said chair, a rod extending through said barrel and making engagement with the pole, a spring in engagement with said rod to tend to press the rod downward, and operator-controlled means for pressing said rod upward, substantially as described.

16. In an electric locomotive, the combination of a bracket having two apertured flanges, a barrel extending through the apertures of said flanges and rotatable therein, a spring supporting the barrel, means limiting upright movement of the barrel, a chair seated on said barrel, a trolley pole pivoted on said chair, a rod extending through said barrel and making engagement with the pole, a spring in engagement with said rod to tend to press the rod downward, and operator-controlled means for pressing said rod upward, substantially as described.

17. In an electric locomotive, the combination of a bracket, a rotatable support extending through said bracket, a spring supporting said support, a hand wheel having a hub surrounding and fixed on said support above

the bracket, a cap on the lower end of said support, a trolley pole pivoted on said support, elastic means constantly tending to tilt the pole to lift its free end, and operator-controlled means adapted to act in opposition to said elastic means to cause the tilting of said pole to lower its free end, substantially as described.

18. In an electric locomotive, the combination of a rotatable barrel, a spring surrounding and supporting said barrel, a trolley pole pivotally supported on said barrel, elastic means supported by said barrel and constantly tending to tilt the pole to lift its free end, and operator-controlled means adapted to act in opposition to said elastic means to cause the tilting of said pole to lower its free end, substantially as described.

19. In an electric locomotive, the combination of a rotatable barrel, an anti-friction bearing surrounding the barrel, a spring surrounding the barrel and supporting said bearing, a trolley pole pivotally supported on said barrel, elastic means supported by said barrel and constantly tending to tilt the pole to lift its free end, and operator-controlled means adapted to act in opposition to said elastic means to cause the tilting of said pole to lower its free end, substantially as described.

20. In an electric locomotive, the combination of a rotatable barrel, a bearing adjustable on the barrel, a spring surrounding the barrel and supporting said bearing, a trolley pole pivotally supported on said barrel, elastic means supported by said barrel and constantly tending to tilt the pole to lift its free end, and operator-controlled means adapted to act in opposition to said elastic means to cause the tilting of said pole to lower its free end, substantially as described.

In testimony whereof I have signed my name, this 10th day of May, in the year one thousand nine hundred and twenty-six.

CHARLES O. BOWEN.
